APPARATUS FOR GRADING POWDERED MATERIAL

Walter Fred Harlow, Quarndon, England, assignor to International Combustion Limited, London, England, a British company

Application January 11, 1943, Serial No. 472,031
In Great Britain March 18, 1942

1 Claim. (Cl. 83—93)

The present invention relates to apparatus which comprises two superposed cyclones associated with a mill equipped with a primary separator which delivers material into the grading device, the fine products passing to a collector, and the returned air from the collector passing to a fan and thence to the mill so that a closed circuit is obtained.

In order to restrict as far as possible the quantity of vented air employed, air is in this arrangement admitted to a housing surrounding the air admission ports described in my application Serial Number 472,030, filed January 11, 1943, this housing embracing the admission ports, and being connected by a pipe to the discharge side of the fan. This arrangement obviates the necessity for the admission of atmospheric air.

One form of construction of the invention is illustrated diagrammatically in the annexed drawing.

In this drawing, *a* is a mill equipped with a primary separator, and delivering into a cyclone device *b* of the kind described in application Serial Number 472,030, filed January 11, 1943, the fine products passing to a collector *c*, and the returned air passing to a fan *d*, and thence back to the mill *a* so that a closed circuit is obtained. The direction of travel of the products and of the air is indicated by the arrows on the drawing. The coarse products rejected by the separator are delivered to a chute *f* by which the raw material to be pulverised is fed to the pulveriser

or mill *a*. With the arrangement described it is necessary to vent the system of surplus air at a suitable point so as to maintain a vacuum to prevent dust emission, the vented air being passed through a bag filter *e*. As it is of importance to restrict the amount of vented air as far as possible in order to restrict the size of the filtering apparatus, which is an expensive one, it is desirable to prevent the entry of atmospheric air into the system. For this purpose a housing embracing the air admission ports *g* of the lower cyclone *s* is connected by a pipe *h* to the discharge side of the fan *d*.

I claim:
15 Apparatus for grading powdered material comprising, a mill equipped with a primary separator, a grading device formed of cyclone separators, a conduit for guiding material from the primary separator into the grading device, a collector, a pipe guiding fine particles from the grading device into the collector, a fan, a conduit connecting the fan with the collector whereby air is drawn from the collector, a discharge tube connecting the fan with the mill whereby air drawn 20 from the collector is supplied to the mill, one cyclone separator having air admission ports 25 therein, a housing embracing said ports, and a pipe connecting the housing with the discharge tube from the fan whereby a portion of air delivered by the fan is supplied to the admission ports.

WALTER FRED HARLOW.
